INVENTOR

JOHN EDWIN FULWEILER

BY

Howson + Howson!
ATTORNEYS

UNITED STATES PATENT OFFICE.

JOHN E. FULWEILER, OF MOYLAN, PENNSYLVANIA.

GRATE.

Application filed January 2, 1925. Serial No. 257.

My invention relates to furnaces, having particular relation to grate structures.

One object of my invention is to provide a grate structure which is characterized by the smooth support provided for furnace cleaning tools; by the ease of replacing damaged grate bars; by the high proportion of cooling surface afforded; by the relatively small danger of breaking the grate bars by the cleaning tools; by the ease of removing adhering clinker; and by the high percentage of air opening even with the smaller sizes of fuel.

Another object of my invention is to provide a grate structure, wherein the angle formed by a line from the lower edge of an upper grate bar to the upper edge of the next adjacent lower bar approximates the angle of repose of the fuel, whereby the maximum amount of air opening may be obtained.

A further object of my invention is to provide a grate structure, wherein the incoming air is caused to pass through heated passages of comparatively narrow dimensions so that the air may be uniformly preheated and the grate bars correspondingly cooled.

A still further object of my invention is to provide a dumping grate, wherein the overlapping grate bars are so disposed as to form longitudinal grooves which are self-cleaning.

With these and other objects and applications in mind, my invention further consists in the details of construction and operation and arrangement, hereinafter described and claimed and illustrated in the accompanying drawings, wherein.

Fig. 1 is a detail perspective view, partially in section, of a furnace embodying my invention;

Fig. 2 is a perspective view of a dumping grate structure embodying my invention; and

Fig. 3 is an enlarged detail transverse sectional view of the longitudinally extending grate bars of the preceding figures.

In the illustrated form of embodiment of my invention shown in Fig. 1, a furnace 1 comprises a front wall 2 and side walls 3. The front wall 2 is provided with a transversely extending beam 4 for removably supporting one end of a grate structure 5, an opposite end of which is supported by a similar beam (not shown). The grate struc-

ture 5 comprises a plurality of lower bars 6 which are removably mounted in laterally spaced relation on the supporting beam 4 and constitute a lower floor surface.

As shown in Fig. 1, the several lower grate bars 6 extend from a furnace opening 7 in the front wall 2 longitudinally of the furnace 1 so as to terminate at a dumping grate section 8 shown in Fig. 2 of the drawing. Each of the lower grate bars 6 is of T-shaped construction and comprises a horizontal flange portion 9 and a central depending web portion 11. The grate structure 5 also comprises a plurality of upper grate bars 12 which are removably mounted on the lower grate bars 6 and constitute an upper floor surface which is more directly exposed to the furnace heat, all as will appear more fully hereinafter. Each of the upper grate bars 12 is also of T-shape formation and comprises a horizontal flange portion 13 and a central depending web portion 14.

As illustrated particularly in Figs. 1 and 3, the several upper grate bars 12 are so disposed as to cover the space intermediate successive lower grate bars 6, the alternate upper and lower grate bars 12 and 6 thus defining a plurality of longitudinally extending depressions 15 adapted to facilitate the cleaning of the grate structure 5 from the furnace opening 7. The flange portions 9 and 13 of the lower and upper grate bars 6 and 12, respectively, also form smooth guideways for cleaning tools.

My invention further contemplates a grate structure having a maximum amount of air opening and also one wherein incoming air may be preheated and the grate bars correspondingly cooled. To this end, the horizontal flange portion 13 of the bars 12 is so positioned as to overlap adjacent edge portions 16 of successive lower grate bars 6 and said flange portions 13 are mounted in spaced relation thereto by means of a plurality of longitudinally disposed vertical spacing lugs 17 extending from the underside of the flange portions 13. The depending web portion 14 is centrally disposed between successive edge portions 16 by horizontal spacing lugs 18 extending from opposite sides thereof.

The spaced mounting of the upper grate bars 12 thus provides a plurality of air inlet passages 19 of comparatively narrow dimensions, causing the incoming air to be con-

siderably preheated and at the same time the grate bars 9 and 12 correspondingly cooled. Moreover, the lugs 17 provide a plurality of supporting points for the relatively hot upper grate bars 12 intermediate the ends thereof, so that the tendency for these bars to sag under operating conditions is prevented; and the vertical lugs 18 prevent the warping of said upper bars 12.

19 In order that the amount of air opening into the grate construction 5 may be a maximum, the spacing lugs 17 are of such dimensions that the angle α , which is formed between the horizontal flange portion 9 of the lower grate bar 56 and a line from the upper edge of the latter to the lower edge of the next adjacent upper horizontal flange portion 13 approximates the angle of repose of the fuel.

20 In Fig. 2 is shown a grate structure 21 of the design shown in Figs. 1 and 2 but further including a pair of central sections 22 and 23 fulcrumed in longitudinally extending side members 24. The latter may be secured to end supporting plates 25 and 26. The end plate 26 may be provided with a door 27 permitting access into the furnace ash pit. The plate 26 may also serve as a mounting for operating levers 28, which are designed to actuate the pivoted grate sections 22 and 23. As may be readily seen from Fig. 2, the sections 22 and 23 are self-cleaning, the longitudinal depressions 15 facilitating the removal of ashes therefrom since they afford no lodgment for ashes when the grate structure 21 is in the dumping position.

While I have shown only one form of embodiment of my invention, for the purpose of describing the same and illustrating its principles of construction and operation, it is apparent that various changes and modifications may be made therein without departing from the spirit of my invention as for instance the use of a grate construction wherein the bars are circular rather than longitudinal. I desire, therefore, that only such limitations shall be imposed thereon as

are indicated in the appended claims or as are demanded by the prior art.

1 claim:

1. A grate structure comprising a plurality of longitudinally extending grate bars in lateral spaced relation, and a plurality of upper grate bars mounted on said lower grate bars, each of said upper grate bars comprising a horizontal body portion provided with spacing lugs whereby a plurality of supporting points may be afforded said upper bars intermediate the ends thereof, said upper bars also comprising vertical webs extending between successive lower grate bars and also provided with spacing lugs, whereby the warping of said upper bars may be substantially prevented.

60 2. An upper grate bar of T-shaped structure provided with horizontal and vertical supporting lugs, and a lower supporting bar for so engaging said lugs as to prevent the warping of said upper bar.

70 3. In combination, a lower longitudinally extending grate bar, and an upper grate bar comprising a horizontal portion and a web portion, said portions being respectively provided with vertical and horizontal spacing lugs engageable with said lower grate bar, whereby the sagging of said upper bar may be eliminated.

75 4. A grate structure comprising a plurality of spaced longitudinally extending bars constituting a lower floor surface, and a plurality of upper grate bars, each comprising a horizontal portion and a web portion, said upper grate bars constituting an upper floor surface positioned in such spaced relation to said lower grate bars as to provide a plurality of air passages, the dimensions of which are such that the fuel is permitted to assume its normal angle of repose on the lower grate bars without extending into said passages sufficiently to pass through the grate structure, and vertical and horizontal spacing lugs formed on the upper grate bars and engageable with said lower grate bars.

JOHN E. FULWEILER.
